H. F. MORRIS.
FURNACE GRATE.
FILED APR. 15, 1921.

Inventor:
Harry F. Morris.
by M. Van Nostrand,
his Attorney.

UNITED STATES PATENT OFFICE.

HARRY F. MORRIS, OF COLLINGSWOOD, NEW JERSEY.

FURNACE GRATE.

Application filed April 15, 1921. Serial No. 461,491.

To all whom it may concern:

Be it known that HARRY F. MORRIS, a citizen of the United States, residing at Collingswood, in the county of Camden and State of New Jersey, has invented certain new and useful Improvements in Furnace Grates, of which the following is a specification.

This invention relates to improvements in forced and natural draft water grates.

The principal object of the invention is to provide means to obtain a horizontal draft in a grate of the class described whereby the finer grades of fuel will not be disturbed, as in grates provided with a direct upward draft, and the same is an improvement on Letters Patent No. 1,261,268 issued to myself and Ritner Shinn, April 2, 1918; Letters Patent No. 1,348,235 granted to myself under date of August 3, 1920 and an application for Letters Patent filed by me March 3, 1921, bearing Serial Number 449,524.

A further object of the invention is to simplify the means of passing air through the grate and to control the quantity of such air, in order to obtain the proper combustion of the fuel on said grate under any and all conditions.

30 A further object of the invention is to provide communicating means between the cored openings in the grate and the surface of said grate, whereby the volume of air to be distributed over the grate surface may be exactly regulated.

In carrying out the above stated, and other, objects I provide a device of new and novel construction whereby the ascending draft of air thru the cored vertical openings 40 in said grate is deflected and distributed horizontally over the surface of the grate, the air openings thru which the air is distributed being so constructed and arranged that the air loses its force or violence before 45 the distribution thereof takes place and the union of the air forces at the point where the air leaves the discs is prevented, obviating a multiplicity of openings with an upward draft which cause a lifting and disturbance of the fuel, detrimental to the burning thereof where coal dirt and the finer grades of fuel are used and causes the tubes, combustion chamber and chimney to fill with unconsumed particles of said fuel.

50 This result I find in practice is absolutely prevented by the use of my indirect hori-

zontal side distribution of the air; more air and more pressure can thus be exerted against small fuel than by any other known method and poorer grades of fuel may be 60 burned faster and a more perfect combustion had thereof.

Where the ascending air from the cored openings in the grate is admitted directly vertically to the fuel bed the said air will 65 leave said openings in jets, with more or less force or violence, according to the pressure thereagainst, lifting and disturbing the fuel.

These and other objects are attained by 70 means of the construction and arrangement of parts, illustrated in the accompanying drawings, wherein:—

Figure 1 is a top plan view in part diagrammatic of the grate;

Figure 2 is a transverse sectional view of the grate on line 2—2 of Fig. 1;

Figure 3 is a top plan view of the discs and grooves in the grate surface;

Figure 4 is a transverse sectional view 80 on line 4—4 of Fig. 3;

Figure 5 is a front elevational view of the disc;

Figure 6 is an inverted plan view of the disc.

Like numerals of reference refer to like parts throughout the drawings.

Referring to the drawings in detail the numeral 10 designates a fire grate provided at the front with a water inlet pipe 11 90 whereby water 12 enters and circulates thru said grate 10. A water outlet pipe 13 is provided at the back of said grate 10 whereby the water after circulating through said grate and being subjected to the heat therein is carried off, thus providing for a continuous circulation of the water through said grate, preventing the overheating and melting thereof. The water flow and return pipes 11 and 13, respectively, are connected with the boiler, water tank or other source of supply.

An air chamber 14 is provided having the door 15 for access thereto and a latch 16 to secure the same in a closed position. 105 This door 15, however, may be secured by means of a bolt or other suitable means as will insure, as near as possible, an air tight connection.

To obtain forced draft air is forced by a 110 blower or other suitable means, through the pipe 17 into and thru the air chamber 14 as

indicated by the arrows in Fig. 2, to the vertical cored openings 18 in said grate 10.

The said grate 10 is provided with the vertical cored openings or holes 18, aforesaid, 5 and the top of said grate 10 is provided with the sunken grooves or channels 22. The sunken grooves 22, substantially oblong in form, radiate horizontally from the cored openings 18 in said grate 10. In said cored 10 openings 18, through which air is admitted to the grate 10, from the air chamber 14, metal discs 19 are positioned, said discs 19 being tapering or conical in form, as particularly illustrated in Fig. 5 of the drawings, 15 to fit within said openings 18, and provided with heads 21, sealing the direct or vertical outlets of the openings 18.

The said discs 19 are provided with flanged heads 21 and beneath said heads are 20 provided with vertical tapering grooves 20 adapted to communicate with the grooves 22 in the upper surface of the grate 10 radiating from the cored openings 18, whereby said heads 21 act as deflectors of the air 25 travelling up the openings 18 from the air chamber 14, thereby causing said air to travel through the vertical grooves 20 and then horizontally through the grooves 22 along the upper surface of the grate 10, instead of directly upwardly and vertically as 30 in the invention hereinbefore cited; the heads 21 closing the vertical outlets of the openings 18.

I have illustrated in the drawings five vertical grooves 20 and five horizontal grooves 22. These various grooves may be of such 35 number as may be found requisite for the purposes herein stated.

It will be noted that the grooves 22 are for 40 air travel under the fire bed and are so positioned that the air travelling through one groove does not communicate directly or gain admission to any other groove radiating from the same or other cored opening 18.

The discs 19 by a slight rotary movement 45 thereof will regulate the amount of air to be

admitted to the grooves 20 in the grate 10 from the openings 18; permitting the full volume of the air ascending through said 50 openings 18 to pass to the grooves 20 if the grooves 22 in the said discs 19 fully communicate therewith. This means of control of the volume of air to be admitted to the grate by the communicating grooves 20 and 22 is particularly illustrated in Fig. 3 of the 55 drawings.

Although in the drawings I have shown certain details of construction and in the preceding, have described such details, it is 60 obvious that I need not be limited thereto otherwise than to the extent to which the appended claims restrict me.

Having thus described my invention what I claim as new and desire to secure by Letters Patent is:—

1. In a grate of the class described, vertical channels therethrough, discs positioned in the outlets of said channels provided with flanged heads adapted to close said outlets, horizontally extending grooves in the upper 70 surface of said grate adapted for communication with said channels and vertical grooves in said discs adapted to establish communication between said channels and said horizontal grooves; said discs being rotatable to open and close such communication, substantially as described.

2. In a grate of the class described, vertical channels therethrough, discs positioned in the outlets of said channels provided with flanged heads adapted to close said outlets, horizontally extending grooves in the upper 80 surface of said grate adapted for communication with said channels and vertical grooves in said discs adapted to establish communication between said channels and said horizontal grooves; said disc being partially rotatable to regulate the degree of such communication, substantially as described.

In testimony whereof I affix my signature.

HARRY F. MORRIS.
